UNITED STATES PATENT OFFICE.

WILLIAM KAPLAN, OF PATERSON, NEW JERSEY.

RUBBER HEEL.

Application filed April 10, 1924. Serial No. 705,493.

To all whom it may concern:

Be it known that I, WILLIAM KAPLAN, a citizen of Russia, residing at Paterson, in the county of Passaic and State of New Jersey, have invented certain new and useful Improvements in Rubber Heels, of which the following is a specification.

This invention relates to rubber heels for boots and shoes, and it has for an object to provide a novel form of rubber heel comprised of a number of sections, whereby renewal of a worn section is possible without renewal of the whole heel, it being a well known fact that heels do not wear evenly throughout the entire area thereof.

For further comprehension of the invention, and of the objects and advantages thereof, reference will be had to the following description and accompanying drawing, and to the appended claims in which the various novel features of the invention are more particularly set forth.

Fig. 1 of the drawings is an underside face view of my improved heel.

Fig. 2 is a transverse vertical sectional view taken on the line 2—2 of Fig. 1.

In constructing my improved rubber heel I provide a number of concentric sections or members which jointly form the heel, three of these sections being here shown and numbered respectively 10, 11 and 12. Of these sections, the outer and intermediate sections 10 and 11 respectively are in the forms of rings or annuli, while the inner section is in the form of a circular block having an opening through the centre thereof to receive a fastening screw 13. The inner section is directly engaged and held by the head 13' of the screw, while the intermediate section 11 is formed with an inwardly projecting lower portion or flange 14 which engages in an undercut peripheral recess in the inner section, thereby preventing displacement of the said intermediate section.

As will be understood, the outer section 10 is the one which is subject to the greatest wear and I have therefore provided a means for holding this outer section in place which permits of its removal and replacement without removing the other sections, or completely withdrawing the screw 13, the latter serving to tighten the said means. As here shown a relatively thin circular plate 16 is fixed on the usual leather element 17 forming the upper part of the heel of the

boot or shoe, and is provided at its periphery with a series of downwardly and outwardly projecting resilient prongs 18 which preferably taper from their roots toward their tips, the extreme tips being bent backward at substantially right angles to the bodies of the tongues as indicated at 18', the bodies of these prongs preferably extending at an angle of forty-five degrees to the plate 16. The tips 18' of the prongs are adapted to engage the upper walls of a number of recesses 20 cut in the inner face of the said outer section 10, while other recesses 21 are formed in the outer wall of the intermediate section 11 to accommodate these prongs when the latter, are withdrawn from the recesses 20.

Fitting upward against the plate 16 is a thicker disk 24 having a beveled edge which fits against the prongs 18 and which is adapted, when the screw 13 is tightened, to move said prongs outward and upward to engage in the recesses 20 and grip the upper wall thereof, the screw 13 being enlarged at its lower portion to provide a shoulder which bears against this disk, the screw passing freely through the disk. I have here shown the socket for the screw in the form of an extension 16' from the plate 16 embedded in the leather heel element 17. The inner and intermediate sections are of somewhat less thickness than the outer section and bear at their upper faces on the disk 24, while the outer section bears at its upper face on the leather heel element 17.

If it is desired to remove the outer section the screw 13 is loosened slightly, allowing the prongs 18 to move inwardly and thereby freeing their tips from the recesses 20 in the said outer section, which can then be withdrawn, and a new one placed in position on the heel, after which the screw is tightened, causing the disk 24 to move up against the plate 16 and force the prongs outward to grip the new section and hold it in place. If the intermediate section also needs replacing the screw is completely loosened, the replacing of the intermediate section being necessitated at rarer intervals than the replacing of the outer section. Furthermore, the construction permits of the outer section being adjusted circularly as desired to turn the worn rear parts toward the front of the heel.

Having thus described my invention what

I claim as new and desire to protect by Letters Patent of the United States is as follows:

- 5 1. In a heel, a top heel element, a rubber heel made up of a number of concentrically arranged sections comprising an outer section, and intermediate section and an inner section, a fastening screw passed through said inner section and engaged with the said 10 top heel element, a plate fixed to the said top heel element and formed with downwardly and outwardly projecting prongs, and a disk adapted to be forced by said screw against the said prongs to move the latter into locking engagement with the said outer section.
- 15 2. In a heel, a top heel element, a rubber heel made up of a number of concentrically

arranged sections comprising an outer section, and intermediate section and an inner section, a fastening screw passed through 20 said inner section and engaged with the said top heel element, a plate fixed to the said top heel element and formed with downwardly and outwardly projecting prongs, and a disk adapted to be forced by said 25 screw against the said prongs to move the latter into locking engagement with the said outer section, said outer section having a number of recesses formed in the inner face thereof to receive the said prongs. 30

In testimony whereof I have affixed my signature.

WILLIAM KAPLAN.
